SHEET SCRUBBING

Olaf M. Hammer, Vandergrift, Pa., assignor to
American Sheet and Tin Plate Company, a cor-
poration of New Jersey

Application November 18, 1935, Serial No. 50,443

8 Claims. (Cl. 15—77)

This invention relates to cleaning the surfaces of sheet-like material and, while not limited thereto, is particularly concerned with scrubbing both sides of substantially flat metal sheets which 5 are relatively thin and brittle.

One of the objects is to provide a scrubbing machine capable of cleaning both sides of flat sheets of extremely thin gages which heretofore, because of their thinness, were necessarily 10 manually scrubbed.

Another object is to scrub without damage both surfaces of a sheet which is naturally brittle, the surfaces and especially the ends of which will in ordinary scrubbing machines be bent or 15 broken.

The usefulness of sheet scrubbing machines has heretofore been restricted, in the steel industries at least, to fairly heavy gage sheets such as No. 26 U. S. S. gage and heavier. Sheets lighter 20 than this have not as a general rule had sufficient rigidity and body strength to withstand the scrubbing action. This condition has necessitated the slow, laborious and costly manual scrubbing of thin gage sheets which is overcome 25 by the present invention.

Furthermore, by means of the present invention one is able to mechanically scrub extremely brittle sheets such as silicon sheets used for electrical purposes.

30 Silicon sheets, having a usual commercial silicon content ranging from .5% to 4.5%, are necessarily brittle and if scrubbed in the usual manner have one or both ends badly bent, torn and even broken by the action of the brushes of conven- 35 tional scrubbing machines.

The present invention is here disclosed in the form of a machine for uniformly cleaning thin gaged silicon sheet metal which is so thin and brittle that the usual scrubbing machines would 40 damage such a product and which therefore commercially has heretofore been manually scrubbed free from loose oxides and dirt following its pickling.

45 Referring to the accompanying drawings: Figure 1 is a partially broken away top view of the sheet scrubbing machine that embodies the principles of the present invention.

50 Figures 2 and 3 are sections respectively taken from the lines II—II and III—III in Figure 1, Figure 3 showing the side of the machine in elevation excepting for one of its driving units.

55 Figure 4 is a section taken from the line IV—IV in Figure 3, this figure showing the exit end of the machine in elevation excepting for certain minor details.

Figure 5 is a section taken from the line V—V in Figure 4 and shows in elevation the major portion of the side of the machine opposite to that shown by Figure 3, excepting for the omission of one of the machine's powering motors. 5

Figure 6 is a wiring diagram of the machine's control system.

Figures 7, 8 and 9 are diagrammatic views showing different phases of the scrubbing operation performed by this machine. 10

Two parallel, and longitudinally extending housing bases 10 are transversely connected by separators 11, these bases being rigidly held together by steel keys 12. On one side of this base assembly is secured a roll drive base 13 while on the opposite side is fastened a motor base 14. On the roll drive base and brush drive motor base are mounted the motors for the pinch rolls and rotary brushes respectively, which are later described. The roll and brush drive and motor bases are secured to the outside portions of the housing bases 10 by the keys 12. 15

On top of the housing bases 10 are equal and oppositely mounted vertically extending roll housings 15 with vertically extending slots or windows 16. These housings go to make up the sides of the machine at the entrance end thereof. Adjacent and abutting said roll housings and extending along the top of the housing bases 10 toward the other or exit end of said machine 20 are vertically extending, equal and opposite brush housings 17. These brush housings each have shaft openings 18 and arcuated slots 19. Adjacent and abutting said brush housings and likewise extending along the top of the housing bases 20 toward the exit end of said machine are another pair of equal and opposite roll housings 20 having windows 16. 25

Likewise adjacent and abutting roll housings 20 and extending along the top of the housing bases 10 and toward the exit end of said machine are equal and opposite brush housings 22 which have shaft openings 18a and arcuated slots 19a. The arcuated slots of these second named brush housings are equal but curve oppositely to the similar slots in the brush housing 17 for reasons to be later described. 30

Finally, adjacent and abutting this second set of brush housings 22 and resting on the housing base 10 are equal and oppositely spaced roll housings 23. These roll housings differ from the first and second named roll housings in that they have a double window 16' and constitute the exit end 35 of the machine.

Thus are made up the base and sides proper 55

of the machine. These bases and sides may be of cast iron. The abutting sectional sides of these roll and brush housings may overlap so as to be held together in any suitable manner, such as by 5 bolts 24.

Mounted transversely of the roll and brush 10 housings and parallel to each other are four pairs of pinch rolls, two pairs of rotary brushes and several pairs of high pressure sprays for respectively conveying, scrubbing and cleaning the 15 sheets as they progress through the apparatus from the entrance and toward the exit end thereof. Separate motor drives are maintained in this preferred embodiment for both the pinch rolls 20 and rotary brushes as well as the operation control of the brushes. Between the pinch rolls, rotary brushes and sprays are top and bottom guides to further aid in conveying the sheets.

The top and bottom guides, as well as the upper 25 and lower pinch rolls, rotary brushes and sprays, are respectively above and below the center line of travel of the sheet material and will hereafter be so designated.

To simplify the details of the above apparatus 30 it will be divided and separately explained as the rotary brush, conveying, guiding, spraying and operating control systems. The correlated action of all systems will then be exemplified in a brief summary of the general operation of said apparatus.

Rotary brush system

The rotary brush system includes at least one 35 pair or unit of stiff fiber or wire brushes which rotate in the same scrubbing direction and above and below the sheet material being cleaned. The preferred embodiment, however, includes two such units of rotary brushes, one pair or unit hereafter designated as A constantly rotating in 40 a scrubbing direction opposite to that of the other pair B.

The pair of brushes A are made up of parallel 45 brushes 30 and 31 located above and below the center line of sheet travel respectively, and rotating in the same scrubbing direction. Likewise in pair B, which parallel the first named pair, are brushes 32 and 33 respectively located above and below the center line of sheet travel but rotating in an opposite scrubbing direction to 50 the pair A.

These brushes 30 to 33 inclusive are mounted 55 on shafts 34, the ends of which extend through the arcuate slots 19 and 19^a of the brush housings 17 and 22, respectively. The ends of these brush shafts 34 are rotatably secured to brush arms 35 to 38 inclusive, located on the outside of the housings. Thus the pair of brushes A are 60 rotatably secured to brush arms 35 and 36 on the free and driven sides respectively, while the ends of the shafts of the pair of brushes B are rotatably secured to brush arms 37 and 38 on their free and driven sides respectively. All of the brush arms are secured for reciprocating movement about stud shafts 39 set in the shaft 65 openings 18 of their respective housings.

In general, each brush arm is made up of a long vertically extending arm to the lower end of which are integrally attached short arms 70 which extend from either side of the vertical extension at an angle of about 45° thereto. The intersection of the short angular arm and the vertically extending long arm constitutes the center of reciprocating movement of each brush 75 arm. At or near the ends of these short exten-

sions are shaft openings into which are rotatably secured the brush shafts 34 just mentioned.

The brush arms 36 and 38 on the driven side 75 are similar in construction to their respective companion brush arms 35 and 37 except that the short extension arms are further extended to include a fixed idler triple width sprocket 40 around which rotates a triple width driving chain 41. Furthermore, arms 36 and 38 carry a housing integral with and between the vertical arm and the lower side of the short extension arm. Within each integral housing is mounted a spring-tensioned, vertically adjustable idler sprocket pin box 42 which maintains the driving chain 41 under constant tension.

Mounted on the cast motor base 14 is a motor 43 which through a shaft and pinion 44 and 45, respectively, drives a gear 46. This gear in turn carries a short drive shaft 47 which is supported in a four-bearing standard 48 having two bearing supports for said shaft 47. Between the bearing supports is a triple width sprocket 49 which drives triple width chain 41.

This driving chain 41, traveling constantly in a counter-clockwise direction, rotates a sprocket 25 50 which is fixed to the brush shaft 34 and drives the lower brush 31 of the pair A. This chain 41 then passes over vertically adjustable idler sprocket 42 and hence to the fixed idler sprocket 40.

Another sprocket 51 is fixed to the shaft of the upper rotary brush 30 and the chain 41 is passed over this sprocket in such a manner that the said brush rotates in the same scrubbing direction as the brush 31 which lies in a plane 35 below the center line of the sheet travel, the brush 30 being above the center line of sheet travel. The triple width chain 41 finally passes from the brush sprocket 51 to the sprocket 49 and the drive cycle for the pair of brushes A is complete.

A companion gear 46' is driven by a gear 46, which former gear rotates a drive shaft 47' mounted in the double bearing 48. Between the bearing supports and on the shaft 47' is mounted 45 a triple-width sprocket 49' which drives a triple width chain 41' in a clockwise direction. This chain then drives the pair of brush rolls B by passing over a drive sprocket 50' which drives the lower brush 33, hence over vertically adjustable idler sprocket 42' and then over a fixed idler sprocket 40'. The chain then passes over a sprocket 51' which, fixed to the shaft 34 drives the upper brush 32 in such a manner that its rotation is in the same direction as the brush 33 55 which lies in a plane below the center line of sheet travel, the brush 32 being above the center line of sheet travel. The triple width chain 41' finally passes from the brush sprocket 51' to drive the sprocket 49' and the drive cycle for the pair 60 of brushes B is complete.

Attached to the top of each of the brush arms 35 to 38 inclusive are worm housings 60. Each of these housings retains a short worm shaft 61 on which is fixedly mounted a worm 62. Worms 65 62 and worm shafts 61 on opposed housings are interconnected by a transverse shaft 63 through clamp couplings 64.

Mounted in each housing 60 and meshing at right angles to the worm 62 is a rotatable worm 70 wheel 65 through which are threaded parallel and longitudinally extending screws 66. These screws also serve to interconnect brush units A and B, thereby transmitting simultaneous reciprocating movement of one brush unit to the other. These 75

- screws 66 are transversely connected and braced by a steel angle 67. To this cross brace 67 is attached a connecting fork 68 which in turn is connected to a crank drive to be later described. 5 This connecting fork in moving back and forth transmits, through parallel screws 66, simultaneous reciprocating motion as desired to the brush arms 35 to 38 inclusive.
- By release of a lock nut wheel 69 and the manual turning of the hand-wheel 70 as secured to the worm shaft 61, the opposing brush arms (for example 37 and 38) are caused to be jointly moved to the right or left, thus varying the position of their brushes 32 and 33 closer or farther 10 away from the center line of sheet travel. Likewise, the brushes 30 and 31 may be shifted toward or away from the center line of sheet travel by the rotation of the hand-wheel and worm shaft by which they are interconnected.
- Such a shifting of one pair of brushes to indirectly or directly vary their pressure on the sheet passing therebetween has no effect on the position or pressure of the other pair of arms, each 15 pair being capable of independent adjustment of the other.

Conveying system

The conveying system includes several pairs of driven pinch rolls all rotating in the same direction whereby the sheet material, as it singly enters the machine, is fed therethrough from one pair of pinch rolls to another.

Thus, there is a pair of pinch rolls 80-80' adjacent the entrance end of the machine. The 35 pinch rolls are made of extra heavy steel pipe to the ends of which are welded shafts 84 which are mounted in suitable bearing blocks or chucks 81. These chucks 81 are located in equal and opposite windows 16 of the roll housings 15. The 40 pinch roll 80' is superimposed on the driven pinch roll 80 and is driven by frictional contact therewith, constant contact being maintained by spring-tensioned screws 85 vertically adjustable through a housing cap 86.

Likewise located about the middle of the apparatus and between the two sets of brush rolls A and B are pinch rolls 81 and 81' which are constructed and arranged similarly to rolls 80-80', but positioned in windows 16 of the equal and opposite roll housings 20.

Beyond the set of brushes B and adjacent the exit end of the machine are two pairs of pinch rolls 82-82' and 83-83' which are constructed and arranged as are the previously mentioned 55 pinch rolls except that they are located in double housing windows 16' of the equal and opposite roll housings 23.

The pinch roll shafts 84 extend at one end through their respective bearing blocks or chucks 87 and respectively carry single and double sprockets 88 and 89 keyed thereto. Thus the 60 shafts of the pinch rolls 81 and 82 each carry a double sprocket 89 while shafts of pinch rolls 80 and 83 each carry a single sprocket 88.

A motor 90 is mounted in the roll drive base 13 and drives a worm gear speed reducer 92 through a shaft 91 and coupling 93. The speed reducer 92, likewise mounted on the base 13, drives the pinch roll 81 through a shaft 94 and a coupling 95. The double sprocket 89 mounted on the shaft 84 drives, through the chain 96, the pinch roll 80 by the single sprocket 88 attached thereto and the double sprocket 89 attached to the shaft of the pinch roll 82. This double

sprocket 89 then drives, through the chain 96, the single sprocket attached to the pinch roll 83.

Guiding system

To further aid in conveying sheets singly through the machine, top and bottom guides are respectively located above and below the center line of sheet travel. These guides not only support and guide the sheet in its travel there-through but also act to brace the sheet against the scrubbing action of the rotary brushes, without which bracing the sheet would become easily bent or broken.

Thus, between driven pinch roll 80 and bottom rotary brush 31 is located a cast guide 100 to support the sheet traveling therebetween. Such a guide is parallel to pinch rolls 80-80' and suitably supported and bolted to brackets 101 cast integral with each of opposite roll housings 15. At spaced intervals across the top face of 20 said guides are grooves which hold short, longitudinally extending wearing strips 102 of bronze or the like. The sheets traveling thereover contact these replaceable wearing strips.

A bottom guide 103, similarly constructed, arranged and supported, rests on integral brackets 104 of roll housings 23 and serves to support the sheet between the lower rotary brush 33 and the pinch roll 82.

Parallel to and between driven pinch rolls 82 30 and 83 and supported on integral brackets 105 attached to the roll housing 23 is another bottom guide 106 which carries longitudinally extending wearing strips 107 replaceably mounted in grooves on the top side thereof. These wearing strips are longer than those previously described and are curved downwardly as they approach the pinch roll 82 to prevent the incoming sheet material from passing therebeneath.

Another bottom guide 108 may be placed between the rotary brush 33 and the guide 103. This guide also extends transversely of the machine and carries removable inserts 109 of wear resistant metal. Such a guide, however, is caused to reciprocate in unison with the movement of 45 the B set of rotary brushes, such a movement being accomplished by attaching its ends to lugs 110 on the lower extension of both the rotary brush arms 37 and 38.

Connecting links 111 are also attached to lugs 50 110, the other ends of which reciprocate in horizontal guide arm bearings 112 attached between brush housing 22 and roll housing 23 by bolts 24. This guide, therefore, is caused to move slightly forward and upward to not only clear brush 33 55 as it swings in and out of contact with the under-side of a sheet being cleaned but also to prevent any appreciable downward bending of the sheet as it clears a top guide 121 above and adjacent the rotary brush 33.

Spanning the space between the rotary brushes 31 and 33 and on either side of the pinch roll 81 are located bottom guides 113 and 114. These guides extend transversely of the apparatus and parallel to the top rotary brushes 30 and 32, respectively. These guides 113 and 114 are mounted on respective brackets 115 and 116 which are integral with the roll housings 20. The tops of these guides are substantially flat and lie in a plane immediately below the center line of 70 sheet travel, the ends of said guide tops curving downwardly slightly to prevent the sheet from passing therebeneath.

As the rotary brush 30 contacts and presses against the top of a sheet passing thereunder, 75

the flat top section of the guide 113 prevents the sheet from buckling or bending under the high pressure and scrubbing action. In a similar manner the top of the guide 114 braces and holds the sheet from buckling or bending as it is scrubbed under pressure by the rotary brush 32.

The top guides consist primarily of two similarly constructed and arranged guides 120 and 121 which are parallel to and immediately above the rotary brushes 31 and 33, respectively. These guides 120 and 121 are respectively supported on brackets 123 and 124 cast integrally with the rotary brush housings 17 and 22.

These fixed top guides both carry removable rectangular bronze or similar wear resistant metal inserts 122 which, together with the guide proper, brace the top side of the sheet material as the rotary brushes therebeneath scrub said sheets under variable pressure. Thus the bending or buckling of the sheet is prevented in a like manner to the bracing of the bottom of the sheet by the bottom guides 113 and 114.

Parallel and between the top pinch rolls 82' and 83' is a guide 125 which carries at spaced intervals removable wear resistant inserts 126, said inserts being of a construction similar to the wear resistant inserts 107 on the bottom guide 106 but in staggered relation thereto. The inserts 126 are turned upward at the end which 30 faces the oncoming sheet so as to prevent the sheet from passing thereover. In fact, the top guide 125 is the reversal of the guide 106 therebeneath.

Spray system

Extending transversely of the apparatus both above and below the center line of the sheet's travel are spray pipes which emit water or other cleaning fluids under high pressure to clean the sheets.

Extending along the one side of the apparatus, parallel to each other and above and below the center line of the sheet's travel, are pipes 130 and 131 suitably connected at one end to a main feeder pipe 132 and closed at the opposite end by caps 133. From pipes 130—131 are short vertical extension pipes 130a and 131a which are of varying lengths to suit the desired positioning of the transversely extending spray pipes properly connected thereto by eis 134.

While these transverse spray pipes may be readily located wherever desired, a thorough cleansing of the sheet can be accomplished by placing the various transverse sprays as indicated in the drawings. The water is emitted from the transverse sprays through small holes 135 at equally spaced intervals and usually at an angle with or against the direction of sheet travel. Thus, for example, is arranged the upper transverse spray pipe 136 which sprays the top side of the sheet just prior to its entrance between the brush 31 and the top guide 120. Likewise constructed and arranged is transverse spray pipe 132 which cleans the top of the sheet just before it enters between the rotary brush 32 and the bottom guide 114.

Other top spray pipes are 138 and 139 which cleanse the top of the sheet as it emerges from the brush 32, guide 114 and pinch rolls 82—82' respectively, the direction of spray in these two cases being, however, opposite to direction of sheet travel.

A transverse spray pipe 140 directs its spray against the bottom of the sheet against its direction of travel as said sheet emerges from between the brush roll 31 and the top guide 120.

while a spray pipe 141 is similarly constructed and arranged as is the spray 139 but so its cleansing action is equal and opposite. Finally, the spray pipe 142 acts on the bottom of the sheet in its direction of travel as said sheet enters between brush 33 and top guide 121.

Operating control system

The operating control system causes the two sets of rotary brushes A and B to be reciprocated so as to enter into or be out of contact with the sheet material passing therebetween.

Such a reciprocation is accomplished by apparatus (disclosed above under the heading "Rotary brush system") connected to a motor 150, 15 which is mounted on a cover frame 151 which rests on top of the roll and brush housings and covers the entire top of the machine.

The apparatus which interconnects the motor 150 and the connecting fork 68 comprises a 20 crank arm 152 which joins the connecting fork 68 with the shaft 153 of the worm gear reducer 154, said shaft carrying at its other end a shaft extension on which is mounted a gear 155. This gear 155 drives a companion gear 156 which in 25 turn rotates a central shaft incorporated in a 180°—4 segment limit switch 157.

At right angles to the gear reducer shaft 153 and interconnected thereto is a shaft 158 which connects the motor 150 with the gear reducer 30 154 through a coupling 159. Interposed between the coupling 159 and motor 150 is a magnetic brake 160.

The proper consequent reciprocation of the two sets of brushes A and B through the connecting 35 fork 68 is caused by suitable electrical connections between the motor 150, 180° segmental switch 157 and triggers 170 and 180.

The trigger 170 is suitably and rotatably mounted on the shaft 171 at the entrance end of the 40 apparatus. A sheet entering the machine depresses said trigger, causing the limit switch 172 (through leverage 173) to operate a motor 150 which in rotating turns the crank arm 152 sufficiently to cause the A set of brushes to contact 45 the sheet. The crank arm movement is limited to 180° by the segment switch 157 which, when 180° cycle of the crank arm is completed, cuts off the motor 150 and applies the magnetic brake 160 which grips the shaft 158 and stops the reciprocating action.

As previously mentioned, the longitudinal screws 66 so connect the two pairs of brushes A and B that when the A set of brushes (30 and 31) are contacting the sheet, the B set of brushes 55 (32 and 33) are out of contact.

This condition exists until the sheet contacts a second trigger 180 located between pinch rolls 82—82' and the upper and lower guides 121 and 103 respectively. Upon such a contact the sheet lifts said second trigger and through suitable leverage 181 causes a limit switch 182 to operate the motor 150 which again turns 180° so as to bring the second set of brushes B into contact with the advancing sheet and at the same time cause the first set of brushes A to be retracted 60 away from the center line of sheet travel.

The magnetic brake 160, together with the 180° segmental switch 157, are common expedients to prevent the overrunning of brush arm movement, the release of said brake from the shaft 158 taking effect as soon as a circuit between either of the limit switches 172 or 182 is completed, and the gripping action taking place as soon as segments of the switch 157 have traveled 180°.

Only one such trigger switch need be used and the leverage system of such triggers may be replaced with a simple electrically operated trigger if so desired without departing from the scope of the invention.

The wiring diagram

The diagram in Figure 6 is greatly simplified. It shows power lines 200 and 201 and the various limit switches are shown as they are when the scrubber stand B is closed and the stand A is open. Each of the limit switches may be considered as having an upper and a lower set of contacts.

When a sheet operates the switch 172 its upper contacts are opened and its lower contacts are closed, which completes a circuit from line 200, through line 202, the solenoid of a relay 203 and through line 204 to the line 201. This closes the contacts of this relay and starts the motor 150 which rotates until the limit switch 157 opens its bottom contacts, due to 180° rotation, and breaks the circuit through the line 202.

The top contacts of the limit switch 157 are now closed, so the closing of the top contacts of the switch 182 by passage of the sheet closes a circuit through a line 205 and energizes the solenoid of a relay 206. This closes the contacts of this relay and energizes the motor 150 until the top contacts of the switch 157 are again opened by 180° rotation of this switch's cam.

The contacts of the relays are in series with a line 207 that connects the motor 150 and the solenoid of the brake 160 to the lines 200 and 201.

General operation

To summarize the foregoing description the following typical operation of the apparatus fully illustrates the principle involved.

With the sprays operating and the pinch rolls rotating to carry sheet material from the entrance to exit end of the machine, thin gaged and possibly brittle sheet S is singly fed into the apparatus between the pinch rolls 80-80'.

This action, partially and diagrammatically shown in Figure 7, causes the trigger 170 to be depressed, which in turn causes the operating control system to move the connecting fork 68 from left to right, said movement causing the set or unit of rotary brushes A to swing into contact with the oncoming sheet. This set or unit of brushes A rotates in the direction of the sheet's travel and thus contacts the front end of the sheet in such a manner that it is not opposed or resisted by the scrubbing action of the brushes.

Such action prevents tearing and bending of sheets which otherwise would be badly damaged. The scrubbing action of the brushes may be varied in intensity or pressure; in any event the top and bottom guides, as previously described, prevent buckling of the sheet through their bracing action.

In the illustrated machine the two sets or units of brushes are so spaced that about one-half of the sheet S is thoroughly scrubbed before its front end strikes the second trigger 180, (Fig. 8). The movement of this second trigger then causes the brush arms 35 to 38 inclusive to reciprocate from right to left. Such action now swings the rotary brushes 30 and 31 out of contact with the sheet S and causes the second or B set of brushes 32 and 33 to make contact with the sheet (Figures 8 and 9).

The rotation of this latter set or unit of brushes B is equal to but in the opposite direction to that

of the first named set of brushes. Thus, the rear half of the sheet is scrubbed both top and bottom in such manner that when the rear of said sheet passes between the rotary brushes 32 and 33 the latter do not oppose or resist the end of the edge 5 of the sheet.

Thus, the front end or half of the forward moving sheet S is scrubbed in a direction equal to the direction of the moving sheet while the rear end or half of the same sheet is scrubbed in a 10 direction opposite to its direction of travel. In other words, the scrubbers always scrub away from the leading and trailing edges of the sheets.

The chain drive for the pinch rolls 80 to 83 inclusive may be covered by suitable guards while 15 guards may also cover the chain drive and gears incidental to the rotary brush drive.

While I have shown and described a specific embodiment of my invention it will be understood that I do not wish to be limited exactly thereto, 20 since various modifications may be made without departing from the scope of my invention.

I claim:

1. A sheet scrubbing machine including the combination of at least two pairs of driven rotary 25 scrubbers and means for mounting and rotating said scrubbers so that either pair may contact the sides of a lengthwise passing sheet while the other pair is free from contact therewith.

2. A sheet scrubbing machine including the 30 combination of at least two oppositely driven rotary scrubbers, means for mounting said scrubbers so that either may contact the same side of an edgewisedly passing sheet while the other is free from contact therewith, and means responsive to movement of said passing sheet for automatically causing said scrubbers to alternately contact the same side of said sheet so that at least the leading and trailing edge portions of the same are contacted only by whichever one of said 40 scrubbers is driven to rotate away therefrom.

3. A sheet scrubbing machine including the combination of means for horizontally feeding a sheet to be scrubbed, at least two oppositely driven upper rotary scrubbers and at least two 45 oppositely driven lower rotary scrubbers for respectively scrubbing the top and bottom sides of said sheet, means for mounting said upper scrubbers so that either may contact the upper side of said sheet while the other is free from the 50 same and for also similarly mounting said lower scrubbers respecting the bottom side of said sheet, and means responsive to movement of said sheet for automatically causing said upper and lower scrubbers to respectively alternately contact said sides of said sheet so that at least the leading and trailing edge portions of the same are contacted only by those of said scrubbers 55 which are driven to rotate away therefrom.

4. A sheet scrubbing machine including the 60 combination of at least two units of spaced parallel scrubbers arranged in tandem parallel relationship, means for driving the scrubbers of each of said units in respectively opposite scrubbing directions, means for feeding a sheet to be 65 scrubbed successively between the scrubbers of said units in a horizontal position, and means for alternately rocking said units during the passage of said sheet therethrough.

5. A sheet scrubbing machine including the 60 combination of at least two units of spaced parallel scrubbers arranged in tandem parallel relationship, means for driving the scrubbers of each of said units in respectively opposite scrubbing directions, means for feeding a sheet to be 75

scrubbed successively between the scrubbers of said units in a horizontal position, means responsive to movement of said sheet for automatically alternately rocking said units into scrubbing contact with said sheet so that at least the leading and trailing end portions of the latter are contacted only by the scrubbers of whichever one of said units is driven by the first named means in a scrubbing direction away therefrom, and supports arranged above and below said sheets at positions opposite said scrubbers when the latter contact said sheet due to rocking of said units.

6. A sheet scrubbing machine including the combination of at least two units of spaced parallel scrubbers arranged in tandem parallel relationship, means for driving the scrubbers of each of said units in respectively opposite scrubbing directions, means for feeding a sheet to be scrubbed successively between the scrubbers of said units in a horizontal position, means responsive to movement of said sheet for automatically alternately rocking said units into scrubbing contact with said sheet so that at least the leading and trailing end portions of the latter are contacted only by the scrubbers of whichever one of said units is driven by the first named means in a scrubbing direction away therefrom, supports arranged above and below said sheets at positions opposite said scrubbers when the latter contact

said sheet due to rocking of said units, the first named means driving the last one of said units through which said sheet passes in a scrubbing direction towards its leading edge portion whereby it is not rocked into scrubbing contact by the third named means until after said leading edge portion has passed, a movable guide arranged close to the lower scrubber of the last named unit and means for moving said guide from the path of said lower scrubber when said last named unit is rocked into contact with said sheet by the third named means.

7. A sheet scrubbing machine including the combination of rotary scrubbing means and means for controlling said scrubbing means so that said scrubbing means rotatively scrubs both sides of a sheet away from both the leading and trailing end portions of said sheet fed lengthwise past the same.

8. A method of scrubbing the surface of flat sheet materials which includes the steps of moving the sheet longitudinally of itself, scrubbing the leading end portion of said sheet material in the same direction as its longitudinal travel and scrubbing the trailing end portion of said sheet material in the opposite direction to its longitudinal travel.

OLAF M. HAMMER.
